UNITED STATES PATENT OFFICE

153,763

DESIGN FOR A DESK WRITING UNIT

Laurie J. Campbell, Erie, Pa., assignor to Louis Marx & Company, Inc., New York, N. Y., a corporation of New York

Application August 12, 1947, Serial No. 140,835

Term of patent 3½ years

(Cl. D74—1)

To all whom it may concern:

Be it known that I, Laurie J. Campbell, a citizen of the United States and a resident of Erie, county of Erie, and State of Pennsylvania, have invented a new, original, and ornamental Design for a Desk Writing Unit, of which the following is a specification, reference being had to the accompanying drawing, forming a part thereof, in which:

Fig. 1 is a side elevational view of a desk writing unit, showing my new design;

Fig. 2 is a top view thereof; and

Fig. 3 is a side view similar to Fig. 1 but showing the pen removed from the stand.

I claim:
The ornamental design for a desk writing unit, as shown.

LAURIE J. CAMPBELL.
